ELECTRICAL CONNECTING MEANS

Harry A. Douglas, Bronson, Mich., assignor to
Lexington Products Corporation, a corporation
of Indiana

Application July 8, 1935, Serial No. 30,281
Renewed March 2, 1938

3 Claims. (Cl. 173—334)

My invention relates to electrical connecting means or devices, and may be embodied in connecting devices adapted to be received by terminal post connections, and the connecting devices, in addition, being adapted for the reception of conductor terminals. More particularly, my invention relates to connection means having a snap-type plug conductor adapted to be received by terminal posts, and also having receiving means adapted for the reception of conductor terminals of the snap-type.

In the drawing accompanying the specification, and forming a part of this application, I have shown, for purposes of illustration, one form which my invention may assume, and in this drawing:

Figure 1 is a central longitudinal sectional view taken through an embodiment of my invention, and including, in addition, a terminal post cooperable therewith, the terminal post being shown partly in transverse section,

Figure 2 is a section taken on the line 2—2 of Figure 1, looking in the direction of the arrows,

Figure 3 is a section taken on the line 3—3 of Figure 2, looking in the direction of the arrows,

Figure 4 is a perspective disassembled view of the plug means and plug terminal receiving means, the housing means having been omitted.

In the illustrated embodiment of my invention, a connector device 19 is adapted for co-operation with a terminal post 11, or the device 10 may be used with another device 10 or any other suitable terminal post receiving means.

The connector device here shown comprises a plug conductor terminal 12, including a generally cylindrical portion 13 provided with an annular furrow 14, the plug having a frustroconical end 15, and extending from the cylindrical portion 13 is a generally cylindrical reduced projection 16.

A housing 17, here shown to be formed of insulating material, is provided with an end wall 18, formed with an aperture 19 of a size to snugly pass the projection 16 of the plug 12. The housing 17, as illustrated, may be tubular and substantially clover-leaf shaped in cross-section, the wall 18 serving as a closure for one end thereof, the other end being open. The particular cross-section of the housing 17 provides communicating longitudinal chambers 20, 21, and 22.

Disposed within the housing 17, is a terminal receiving means 23, best illustrated in Figure 4.

55 The receiving means 23, as here shown, com-

prises a portion 24, substantially double-ogee shaped in transverse section, and providing generally cylindrical loops 25 and 26, oppositely disposed, the free ends of the loops 25 and 26 being relatively small in longitudinal length to form tip portions 27 which are turned radially inwardly, as shown at 28 in Figure 2. The margins of the tip portions 27 diverge sharply to form a bevel part 29, and from the bevel parts 29 the margins of the loop diverge gradually, the right margin, as viewed in Figure 4, to the crest 30 of the double ogee curve, and the left margin to a point approximately horizontal with the highest point of the loops 25, 26, where it extends laterally and then angularly upwardly to form 15 an ear portion 31. An aperture 32 is provided in the ear 31, the aperture 32 being of a size to snugly pass the projection 16 of the plug terminal 12.

In assembling the connector device 10, the projection 16 of the plug terminal 12 is inserted into the aperture 19 in the end wall 18 of the housing 17, the insertion of the projection 16 being limited by engagement of the shoulder formed by the cylindrical portion 13 and reduced projection 16 with the end wall 18. Next, the terminal receiving means 23 is inserted into the housing 17, with the loops 25, 26 disposed within the chambers 21, 22, and the ear portion disposed within the chamber 20 and abutting the end wall 18. As best shown in Figure 2, the housing 17 is provided with a partial central partition 33 formed by continuing upwardly the adjacent surfaces of the inner peripheries of the chambers 21, 22, and the partition extends longitudinally from the end wall 18 to the opposite open end of the housing 17.

With the terminal receiving means 23 in position within the housing 17, the end of the projection 16 extends through the aperture 32 in 40 the ear 31, and this end is then spread radially outwardly as by bending, pressing, spinning, or in any other suitable manner, and against the adjacent surface of the ear 31 to thereby secure the plug terminal 12, housing 17, and terminal 45 receiving means 23 tightly together.

The terminal receiving means 23, it will be appreciated, may be formed from a single strip of suitable resilient, electric current conductive material, and the loops 25, 26, are of a slightly 50 smaller cross-sectional extent than the space within the chambers 21, 22, so that the loops 25, 26 may be flexed substantially radially within the respective chambers.

In Figure 3 is shown a plug conductor terminal 55

33 cooperable with the loop 26, although it will be understood that either one of the loops 25, 26 may cooperate with the plug conductor terminal 33, or both loops concurrently may receive such plug conductor terminals. The terminal 33 includes a generally cylindrical portion 34 provided with an annular furrow 35, the terminal 33 having a frusto-conical end 36. The terminal 33 may be fastened to a conductor 37 disposed therein by swedging, as indicated by the swedge indentations 38. When the plug terminal is inserted, for example, into the loop 26, the frusto-conical end 36 serves to cam the tip portion 27 of the loop 26 radially outwardly, further inserting movement causing the tip portion 27 to snap into the annular furrow 35. Conversely, when it is desired to remove the plug terminal 33, removal movement thereof will cause the tip 27 to be cammed radially outwardly by reason of the curved surface of the annular furrow 35 slidably engaging therewith, further removal movement causing the tip portion 27 to ride over the cylindrical portion 34 and finally disengaging the plug terminal 33.

25 The terminal post 11, as shown in Figure 1, is adapted to receive the plug terminal 12, and comprises, generally, a body 39, mounted on a base 40, and provided with a terminal receiving aperture 41. A detent means 42, suitably contained within the post 11, is biased to operative position with respect to the aperture 41 by means of a spring 43.

35 When the plug terminal 12 is inserted into the aperture 41, the frusto-conical end 15 serves to cam the detent means 42 downwardly, further inserting movement causing the hemispherical portion of the detent means to snap into the annular furrow 14. The post 11 may be electrically connected to any suitable apparatus (not shown).

40 From the foregoing it will be apparent to those skilled in the art that the illustrated embodiment of my invention provides a new and improved electrical connection means, readily and conveniently constructed, assembled, and mounted on a support, and accordingly, accomplishes at least the principal object of my invention. On the other hand, it also will be obvious to those skilled in the art that the illustrated embodiment of my invention may be variously changed and modified, or features thereof, singly or collectively, embodied in other combinations than those

50

illustrated, without departing from the spirit of my invention, or sacrificing all of the advantages thereof, and that accordingly, the disclosure herein is illustrative only, and my invention is not limited thereto.

5 I claim:

1. Electrical connecting means, comprising: a member formed of a single piece of sheet-metal, opposite marginal portions of said member being bent to form a pair of generally tubular loops 10 permanently disposed in spaced apart side-by-side relation and integrally joined by a reentrant portion extending between said loops, the outer surface of said reentrant portion being trough-like and of curved cross-section, said member 15 including a tab portion integral with said reentrant portion and extending laterally from said trough-like curved surface so that the line of junction between said trough-like surface and said laterally extending portion is curved. 20

2. A one piece connector including a pair of spaced apart substantially parallel tubular split receptacles adapted to receive terminals, a trough-like portion extending immediately inwardly between and forming portions of said receptacles, a tab projecting transversely from said trough-like portion, and integral portions joining said receptacles with said tab means whereby to reinforce said connector at the junction between said tab and said trough-like portion, the 25 junction being non-rectilinear. 30

3. A one piece connector including a pair of spaced apart substantially parallel tubular split receptacles adapted to receive terminals, a trough-like portion extending immediately inwardly between said receptacles, tab means projecting transversely from one extremity of said trough-like portion, integral portions joining said receptacles with said tab means to provide and reinforce the junction between same and an aperture extending substantially parallel to the axes of said receptacles provided in said tab through which electrical connection means may be extended for connection with said tab, said aperture being located as near as is possible to the bottom wall of said trough-like portion to permit satisfactory connection of said means adapted to be extended through said aperture and connected to said tab means, said junction being non-rectilinear. 40 45

50 HARRY A. DOUGLAS.
